UNITED STATES PATENT OFFICE.

WILLIAM CODMAN, OF PROVIDENCE, RHODE ISLAND.

DESIGN FOR A METAL BORDER STRIP FOR A TRAY OR SIMILAR ARTICLE.

Application filed February 9, 1924. Serial No. 8,587. Term of patent 7 years.

To all whom it may concern:

Be it known that I, WILLIAM CODMAN, a citizen of the United States, residing at Providence, in the county of Providence and State of Rhode Island, have invented a new, original, and ornamental Design for a Metal Border Strip for a Tray or Similar Article, of which the following is a specification, reference being had to the accompanying drawing, forming part thereof.

The drawing is a plan view of a metal border strip for a tray or similar article, showing my design.

I claim:

The ornamental design for a metal border strip for a tray or similar article, as shown.

In testimony whereof I have signed my name to this specification in the presence of two subscribing witnesses.

WILLIAM CODMAN.
